UNITED STATES PATENT OFFICE.

EMORY BARNES, OF MOUNT PLEASANT, MICHIGAN.

LIFTING AND FORCE PUMP.

SPECIFICATION forming part of Letters Patent No. 224,509, dated February 17, 1880.

Application filed November 3, 1879.

To all whom it may concern:

Be it known that I, EMORY BARNES, of Mount Pleasant, in the county of Isabella and State of Michigan, have invented an Improvement in Lifting and Force Pumps, of which the following is a specification.

The nature of my invention relates to certain new and useful improvements in that class of water-elevators known as "lifting and force pumps," wherein great economy, durability, and efficiency are required.

The invention consists in the peculiar construction, combination, and arrangement of parts, as more fully hereinafter set forth.

In the drawings, Figure 1 is a vertical central section. Fig. 2 is a detached and perspective view of the barrel. Fig. 3 is a detached and perspective view of the section above the barrel, forming a water and valve chamber with offset discharge-neck and attachments. Fig. 4 is a like view of the upper piston-chamber.

Like letters refer to like parts in each figure.

In the accompanying drawings, which form a part of this specification, A represents a pump barrel or cylinder with an open or perforated bottom, and with a flange top, a, provided with a central opening, b, which forms a seat for the double valve B, which is sleeved on the piston-rod C. Within this barrel the hollow piston D reciprocates, and is provided with annular channels c to form water-packing. Seated upon the top of this hollow piston and sleeved upon the piston-rod C is the valve F, the throw or play of which is controlled by the stop d on the piston-rod. This valve B is a double one—that is to say, it is composed of an upper and lower valve connected by a hollow neck, the lower valve having its seat in the flange top a of the barrel. G is a short cylinder fitting by a ground joint upon this flange top, and is provided with an outlet-pipe, H, the outer end of which terminates in an enlarged recess, e, the vertical walls of which are threaded to engage with the bottom of the externally-threaded shell I.

A valve-seat, f, is formed within this recess to receive the valve J. The spider K is placed over this valve, its foot-ring g resting upon the bottom of the recess being ground to place, 50 and the shell I being screwed to place secures the spider.

L is a cylinder fitting with a ground joint upon the top of the cylinder G. This cylinder is provided with an internally and externally projecting flange, h, and by means of bolts is secured to the flange top of the barrel. The internally projecting portion of the flange leaves a contracted opening into the bottom of the cylinder, in which there is a seat for the 60 upper valve of the double valve B, heretofore described.

Below the hollow piston N, which reciprocates within the cylinder L, which is open at top, the valve M is sleeved upon the piston-rod, and has its seat on the under side of the piston, its throw being confined by the stop i. The upper end of this piston-rod is threaded to receive the pitman-connection O, which, when in place, secures the piston N in position.

This pump is designed to be submerged in water, and may be placed in any desired position.

The operation of this pump is so obvious 75 from its construction that a further explanation thereof is deemed unnecessary in this connection.

What I claim as my invention, and desire to secure by Letters Patent, is—

A double-acting lifting and force pump, consisting of the barrel A, double valve B, piston-rod C, hollow piston D, valve F, cylinder G, outlet-pipe H, shell I, valve J, spider K, cylinder L, valve M, hollow piston N, and pitman-connection O, when the parts are constructed and combined to operate substantially as shown and described.

EMORY BARNES.
